LASTING MACHINE

Bernhardt Jorgensen, Marblehead, Mass., assignor to United Shoe Machinery Corporation, Flemington, N. J., a corporation of New Jersey

Original application October 10, 1950, Serial No. 189,407. Divided and this application January 5, 1952, Serial No. 265,107

25 Claims.

(Cl. 12—12)

1

This invention relates to lasting machines and is herein shown as embodied in a machine for lasting the ball portions of shoes from the toe-end portions to the shank portions, the present application being a division of a copending application, Serial No. 189,407, filed on October 10, 1950. In its general organization the machine is similar to that shown in United States Letters Patent No. 2,614,275, granted October 21, 1952 upon my application, and in some aspects the invention provides improvements in that earlier machine. It is to be understood, however, that this is only an illustrative embodiment and that the invention is not limited to the particular organization shown.

In general accordance with the disclosure of the above-mentioned Patent No. 2,614,275, the machine is provided with grippers which grip the margin of the upper at the opposite sides of the ball portion of the shoe and pull the upper lengthwise of the last, and with wipers which after the pulling of the upper wipe its margin inwardly over an insole on the last and cause it to adhere to the insole, the grippers and wipers and other elements of the machine being operated by fluid pressure.

In accordance with a feature of the invention the machine includes novel means for varying, in the operation of the machine on shoes of different sizes, the distance lengthwise of the shoes of the effective engagement of the wipers with the shoe uppers. For the purpose in view the upper at each side of the shoe is operated upon by a pair of wipers arranged to extend continuously, one beyond the other, along the side of the shoe and relatively movable lengthwise of the shoe while maintaining such continuity, and through such relative movement of the wipers the distance lengthwise of the shoe of their engagement with the upper is determined. In the operation of the machine the two wipers of each pair are moved inwardly widthwise of the shoe with substantial components of bodily movement lengthwise of the shoe toward its toe end, and to effect their relative movement for the purpose above described that component of movement of the wiper which is nearest to the toe end of the shoe is variably limited independently of the movement of the other wiper. In presenting the shoe to the machine the operator positions it lengthwise, regardless of its size, in proper relation to the grippers as determined by sight with reference to the grippers, and accordingly the toe-end faces of shoes of different sizes occupy different positions in the machine. Conveniently, therefore, a member engaging the toe-end

2

face of each shoe and positioned as determined by the shoe is utilized for limiting as described the above-mentioned components of movement of the wipers nearest to the toe end of the shoe, this member being arranged to determine variably the positions of stops which act on links pivotally connected to these wipers. A further effect of this wiper-controlling means is to terminate the engagement of the wipers with the upper at the same distance from the end of the toe of each shoe regardless of variations in the positions of the different shoes. Insurance is thus afforded that if the shoes have therein upstanding pulling-over tacks at the sides of the toes the wipers will not engage these tacks. In the construction shown the above-mentioned links extend initially in convergent relation toward the toe end of the shoe and in the operation of the wipers they approach a parallel relation to each other. As the links, therefore, continue to swing toward parallel relation after their movements lengthwise of the shoe have been terminated by the stops, they impart to the wipers connected therewith components of movement reversely toward the heel end of the shoe relatively to the other wipers. This serves to counteract any tendency for these wipers to deflect the portions of the upper which they engage in directions toward the toe end of the shoe.

The invention still further provides novel means for operating the wipers. In general accordance with the disclosure of the previously mentioned Patent No. 2,614,275, the portions of the wipers which are farthest from the toe end of the shoe are moved inwardly toward and over the shoe by arms which are mounted for swinging movements about axes extending heightwise of the shoe, and portions of the wipers located nearer the toe end of the shoe are at the same time moved inwardly by other arms mounted for swinging movements about other similarly extending axes, the wipers being swung farther inward relatively to the first-mentioned arms by continued movements of these other arms after the first-mentioned arms have come to a stop. In the construction herein shown novel connections are provided between the other arms and the first-mentioned arms for swinging the latter inwardly by the movements of the other arms until the wipers have partially completed the wiping operation and for thereafter terminating the movements of the first-mentioned arms but for holding them positively against retractive movements during further movements of the other arms to complete the wiping operation. In the construction shown these connections in-

clude plates movable bodily by the other arms and provided with slots in which lie rolls mounted on the first-mentioned arms, and in the course of the wiping operation these plates are swung to positions such that by reason of the relation of their slots to the rolls no further movements are imparted to the first-mentioned arms during continued movements of the other arms, the arrangement, however, being such as to prevent positively any retractive movements of the first-mentioned arms.

The above and other features of the invention, including various novel details of construction and combinations of parts, will now be more particularly described with reference to the accompanying drawings and thereafter pointed out in the claims.

In the drawings,

Fig. 1 is a view partly in right-hand side elevation and partly in section of a portion of the machine in which the invention is herein shown as embodied;

Fig. 2 is mainly a plan view of a portion of the machine, showing the wipers and their operating mechanism, with parts in section and others broken away;

Figs. 3 and 4 are views generally similar to a portion of Fig. 2, but showing the parts as they appear at different times in the operation of the machine; and

Fig. 5 is a view partly in front elevation and partly in section, showing the grippers and the wipers.

For positioning the shoe heightwise in the machine there is provided a forwardly and rearwardly extending lever 2 (Fig. 1) which is pivotally mounted substantially midway between its front and rear ends on a pin 4 supported in two members 6, only one of which is shown, extending upwardly at opposite sides of the lever 2 from a substantially horizontal frame casting 8 to which they are secured. Mounted for adjusting movement upwardly or downwardly in a guideway in the front end of the lever 2 is a shoe rest member 10 on the lower end of which are formed two presser feet 12 spaced apart widthwise of the shoe as shown in Fig. 5 and arranged to engage the insole at the ball portion of the shoe, these presser feet having insole-engaging teeth thereon and by reason of their spaced relation serving further to position the shoe with respect to lateral tipping movement. The member 10 is adjustable heightwise of the shoe relatively to the lever 2 by means of a screw 14 which is threaded therein, the screw having a head 16 a portion of which lies in a slot in the lever 2 to prevent upward or downward movement of the screw relatively to the lever. To assist in holding the member 10 in adjusted position there is mounted in the lever 2 a spring-pressed pin 18 having a conical front end arranged to enter one or another of a plurality of recesses 20 in the head of the screw. Secured to the upper end of the screw is a member 22 connected by a universal joint 24 to a rod 26 through which the screw is turned, as more fully disclosed in application Serial No. 189,407.

Pivottally mounted on a pin 28 in the rear end of the lever 2 at the opposite sides of the lever respectively are two downwardly extending links 30 of a toggle 32, the lower ends of these links being pivotally connected by a pin 34 to a toggle link 36 which is pivotally mounted at its lower end on a pin 38 in a casting 40 on the frame. Connected to the lever 2 and to the links 30 is

a spring 42 which tends to straighten the toggle 32. Threaded in the upper end of the link 36 is a screw 44 on which is mounted a lock nut 46 in engagement with a washer 48. This washer overlaps portions of the link 36 and of the two links 30 and accordingly limits straightening of the toggle under the influence of the spring 42. Initially, the toggle is in its straightened position, as shown in Fig. 1, and accordingly the shoe rest member 10 is held positively against any upward movement in response to pressure of the shoe thereon.

Further to assist in positioning the shoe there is provided another shoe-rest member 50 on which are two downwardly extending bosses 52 (Fig. 2) spaced apart widthwise of the shoe and having smooth faces arranged to engage the toe end of the insole. The member 50 is of angular shape to provide a downwardly extending portion from which extends rearwardly an arm 54 pivotally mounted at its rear end on a pin 56, this pin being supported in lugs extending upwardly from a slide 58 which is guided for forward and rearward movements in a holder 60 fast on a casting 62 on the frame. Mounted in a socket in the slide 58 and abutting at its rear end against a bracket 64 secured to the casting 62 is a spring 66 a portion of which surrounds a positioning rod 68 secured to and extending forwardly from the bracket 64. This spring tends to move the slide 58 in a forward direction, its forward movement being limited by its engagement with a stop 70 on the holder 60. Secured on the downwardly extending portion of the angular shoe-rest member 50 is a piece of leather 72 arranged to engage the toe-end face of the shoe when the operator presents the shoe to the machine, and in thus presenting the shoe the operator will move the member 50 and the slide 58 more or less in a rearward direction against the resistance of the spring 66 by the pressure of the toe-end face of the shoe thereon for a purpose more particularly hereinafter explained.

Mounted in a socket in the slide 58 is a spring 74 which tends to swing the shoe-rest member 50 in an upward direction about the pin 56 and holds it against a roll 76 mounted on a pin 78 which is supported in the lower ends of two links 80 extending upward respectively at opposite sides of the lever 2. These links are pivotally connected at their upper ends by a pin 82 to the front end of a forwardly and rearwardly extending lever 84 pivotally mounted substantially midway between its front and rear ends on a pin 86 in the upper ends of the members 6. Extending through vertical slots 88 in the two links 80 is a pin 90 supported in a member 92 which is fast on the casting 8, this pin-and-slot arrangement permitting limited upward and downward movements of the links. Secured to the rear arm of the lever 84 is a leaf spring 94 which bears on the front arm of the lever 2 and tends to swing the lever 84 in a clockwise direction with reference to Fig. 1 as permitted by the slots 88 and the pin 90. Threaded in the rear end of the lever 84 is a screw 96 arranged to engage the upper face of the rear arm of the lever 2 and thereby to limit any swinging movement of the lever 84 relatively to the lever 2 under the influence of the spring 94. It will be evident that by means of the screw 96 the lever 84 may be adjusted relatively to the lever 2 to determine adjustably the position heightwise of the machine of the shoe-rest member 50 which engages the toe end of the shoe independently of adjustment of the shoe-rest mem-

ber 10 which engages the ball portion of the shoe. While the shoe is held by the operator after it has been presented to the machine it is automatically positioned widthwise in proper relation to the lasting instrumentalities by opposite side clamps 98. These side clamps include levers 100 (Fig. 2) pivotally mounted between their front and rear ends on vertical studs 102 supported in the casting 62. Formed on the levers 100 are gear sectors 104 in engagement with each other to equalize the movements of the levers. The rear ends of the levers are in engagement with the rounded outer ends of pistons 108 movable toward and from each other in a cylinder 108 formed in the casting 62. Bosses 110 of reduced diameter formed on the inner ends of the pistons provide an annular space between the pistons for the admission of operating fluid when the pistons are in their innermost positions. Fluid is thus admitted between the pistons at the proper time from the source of fluid supply. Pivotally mounted on a vertical pin 112 supported on the front end of each lever 100 in the construction herein shown is a curved bar 114 extending substantially equal distances forwardly and rearwardly of the pin, and pivotally mounted on each end of this bar to swing about an axis extending heightwise of the shoe is a block 116 to which is secured a strip of leather 118 arranged to engage the shoe upper. As shown in Fig. 2, the two leather strips at each side of the shoe extend toward each other beyond the blocks 116, and connected to the ends of the strips which are nearest to each other is a light spring 120 which steadies the blocks 116 and prevents either of them from swinging too far about its connection with the bar 114 when there is no shoe in the machine. Connected, moreover, to each lever 100 and to the bar 114 thereon near the pin 112 is a spring 122 which prevents uncontrolled swinging movement of the bar about the pin 112 and holds it approximately in the relation to the lever 100 which it assumes when clamping the shoe. It will be evident that the foremost blocks 116 and their leather facings clamp the shoe at the opposite sides of its ball portion and that the rearmost blocks and their facings clamp it at the opposite sides of the toe. By this construction the shoe is centralized bodily widthwise and is held firmly in the position thus determined in the desired relation to the lasting instrumentalities. For returning the levers 100 upon release of the fluid from the cylinder 108 there is provided a spring 124 connected at one end to a rearward extension 126 of the right-hand lever and at the other end to a rod 128 secured in the casting 62 (see Fig. 1). The connection between the spring and this rod comprises an eye-bolt 130 and a hand nut 132 threaded thereon for adjusting the tension of the spring.

After the shoe has been positioned laterally as above described by the side clamps 98 it is clamped against the shoe rest members 10 and 59 by a toe rest 134. This toe rest comprises a rubber pad 136 mounted on a holder 138 guided for tipping movement about an axis extending lengthwise of the shoe in a block 140 which is mounted on the upper end of a piston 142 movable upwardly in a forwardly inclined direction in a cylinder 144 to the lower end of which fluid is admitted at the proper time from the source of supply.

For pulling the upper the machine is provided with a pair of grippers 146 (Fig. 5) ar-

ranged to grip the margin of the upper respectively at the opposite sides of the ball portion of the shoe in locations between portions of the upper previously fastened to the insole by side pulling-over tacks t (Fig. 3) and, it may be, by staples s used in lasting the shank portion of the shoe. These grippers and their operating and controlling means are fully described in the copending application, Serial No. 189,407, of which the present application is a division, and no further description thereof herein is necessary.

The wipers for wiping the marginal portion of the upper inwardly over the insole after the pulling of the upper by the grippers include what may be termed, for purposes of designation, main wipers 148 (Figs. 2, 3 and 4), each of these wipers having a wiping edge arranged to extend lengthwise of the shoe and curved to extend also inwardly widthwise of the shoe heelwardly of the ball line. Each wiper 148 is pivotally mounted at its front end to swing widthwise of the shoe about a stud 150 carried by the inner end of a bar or plate 152 secured on the upper face of a forwardly and inwardly curved arm 154 of which it serves as an extension, the arm being mounted to swing about a vertical pin 156 on the frame casting 8. By means hereinafter described the two arms 154 are swung inwardly toward the shoe to impart bodily inward movements to the wipers by forwardly and rearwardly extending levers 158 which are pivotally mounted between their front and rear ends to swing about studs 160 extending downwardly from the frame casting 8. Secured to each lever 158 underneath is a plate 162 having therein a slot 164 arranged to extend lengthwise of the shoe, and lying in this slot is a roll 166 (Figs. 3 and 4) mounted on a stud 168 extending upwardly from the rear end of the corresponding wiper 148. By reason of the locations of the pins 156 the wiper 148 carried by each arm 154 has a substantial component of bodily movement lengthwise of the shoe toward its toe end as it is carried inwardly by the arm, and during this movement of the arm the rear end of the wiper is guided and controlled by the slot 164, the roll 166 moving rearwardly along the slot. Through the roll, moreover, the rear end of the wiper is moved inwardly by the lever 158 as the arm 154 is swung inwardly. For maintaining the wipers in a heated condition each plate 162 has secured thereto underneath an electrical heating element (not herein shown).

Extending upwardly from each arm 154 in fixed relation thereto is a pin 170 having a reduced upper end portion lying in a slot 172 formed in a link 174 which is pivotally mounted on a stud 176 on the corresponding wiper-operating lever 158. The link 174 is made in two parts spaced vertically from each other, the two parts acting as one. Between the two parts of the link is a plate 178 pivotally mounted on a pin 180 on the link to swing relatively to the link. Formed in this plate is a slot 182 which includes a comparatively short portion 184 and a longer curved portion 186 in angular relation to each other. Lying in this slot is a roll 188 mounted on the reduced upper end portion of the pin 176. The plate 178 is controlled with respect to swinging movement about the pin 180 by a link 190 which connects it to the front end of the lever 158. This link includes a member 192 pivotally mounted on the plate 178 and a screw 194 threaded in this member and extending through a block 196 pivotally

mounted on the lever 158. An enlarged head 198 on the screw engages one side of the block 196 and a collar 200 fast on the screw engages the other side of the block. It will therefore be evident that by turning the screw 194 the plate 178 may be adjusted about the pin 180.

From Fig. 2 it will be understood that when the parts are in starting positions the roll 188 on each pin 170 lies in the shorter portion 184 of the slot 182, this portion of the slot being in such relation to the link 174 that as the front arm of the lever 158 begins to swing inwardly the link acts positively through the plate 178 on the pin 170 to swing the wiper-carrying arm 154 in an inward direction, thus causing the wiper 148 to be moved inwardly with a component of movement toward the toe end of the shoe to wipe the upper over the insole. By reason of the manner in which the wiper is controlled by the slot 164 in the plate 162 it receives at this time no substantial swinging movement about the stud 150 as it is moved bodily inward. Since the link 190 is pivotally connected to the lever 158 at a greater distance from the fulcrum of the lever than the link 174 and since the link 174 is controlled by the upper end of the pin 170 in the slot 172, the lever 158 in its swinging movement acts through the link 190 to swing the plate 178 progressively about the pin 180 in the link. When the parts, therefore, have arrived in the positions indicated in Fig. 3, the roll 188 is at the junction of the two portions 184 and 186 of the slot 182 in the plate. As the lever 158 thereafter continues its swinging movement it is no longer effective to swing the arm 154, since by reason of the position of the portion 186 of the slot 182 and the continued swinging movement of the plate 178 about the pin 180 the plate no longer applies to the roll 188 any force tending to swing the arm 154 farther inward. The arm, therefore, remains stationary while the other parts move from the positions in which they are shown in Fig. 3 to those in which they are shown in Fig. 4, the link 174 being moved inward relatively to the pin 170 and the plate 178 continuing to swing about the pin 180. In this manner the wiper 148 is swung inwardly by the lever 158 about the stud 150 to complete the wiping operation, especially in locations forwardly of the ball line. While the arm 154 is swung no farther inwardly at this time, it is locked positively against any retractive movement by reason of the fact that the slot 172 in the link 174 and the portion 186 of the slot 182 in the plate 178 are in crosswise relation to each other. That is, the pin 170 cannot move outward along the slot 172 because of the position of the roll 188 in the slot 182. The construction thus provided affords insurance that regardless of the resistance of the shoe the wipers 148 will always be moved inwardly to the desired limits by the arms 153 before they are swung about the studs 150 to complete the wiping operation.

Each wiper 148 has in its lower face a recess in which is mounted a supplemental wiper 202 arranged to extend nearer to the toe end of the shoe for the purpose of varying the range of action of the wipers lengthwise of the shoe. The wiper 202 in the construction shown has an arcuate wiping edge of convex contour and is pivotally mounted on a pin 204 in the wiper 148 to expose more or less of its wiping edge rearwardly beyond the wiper 148. Pivotally connected to the two wipers 202 are rearwardly extending links 206 provided with slots 208 in which lie studs 210

extending upwardly from a crossbar 212 secured by a screw 214 to the rearwardly extending arm 54 (Fig. 1) of the shoe-rest member 50. As hereinbefore explained, when the operator presents a shoe to the machine he positions its toe-end face against the leather facing 72 on this member and moves the member more or less in a rearward direction against the resistance of the spring 66. Accordingly, the studs 210 are moved more or less rearwardly by this member as determined by the position of the shoe. Springs 216 connected to the wipers 202 tend to move them in rearward directions about the pins 204 and hold them initially in positions in which comparatively long portions of their wiping edges are exposed. It will be understood that when the wipers 148 are moved inwardly by the arms 154 with substantial components of rearward movement lengthwise of the shoe the wipers 202 receive the same movements until the rearward movements of the links 206 are stopped by engagement of the studs 210 with the links at the front ends of the slots 208. Thereafter the wipers 202 receive no further components of movement lengthwise of the shoe during any further such movements of the wipers 148. In this manner the distance lengthwise of the shoe of the engagement of the wipers with the upper is variably determined in operating on shoes of different sizes and insurance is afforded that the engagement of the wipers with the upper will terminate at the same distance from the end of the toe regardless of any variations in the positions of different shoes lengthwise in the machine, the position of each shoe in that respect being determined by sight with reference to the grippers. If the shoes operated upon, therefore, have at the sides of the toes upstanding pulling-over tacks 7 (Fig. 3), insurance will be afforded that the wipers will not hit these tacks. In order to vary the distance from the end of the toe at which the wipers terminate their engagement with the upper, the crossbar 212 has therein a slot 218 through which the screw 214 extends to permit it to be adjusted relatively to the shoe-rest member 50.

By reference to Fig. 2 it will be seen that the above-mentioned links 206 diverge from each other initially in directions toward the heel end of the shoe, and by the operation of the wipers they are swung into substantially parallel relation to each other, as illustrated in Fig. 4. Accordingly, after the movements of the supplemental wipers 202 toward the toe end of the shoe have been stopped by engagement of the studs 210 with the links in the manner above described, the links act during further inward movements of the wipers, especially the swinging movements thereof about the studs 150 after the termination of their bodily inward movements, to move the supplemental wipers 202 relatively to the wipers 148 in directions toward the heel end of the shoe. This serves to counteract any tendency of the wipers 202 to deflect the margin of the upper toward the toe end of the shoe in the wiping operation.

To afford better insurance that the portions of the margin of the upper in locations where the bottom of the inverted shoe slopes downward heelwardly of the ball line will be properly wiped inwardly over the insole and secured to the insole by adhesion, there is provided under the front end portion of each wiper 148 an auxiliary wiper 220 (Figs. 1 and 2). This wiper includes a thin plate 222 formed on a block 224 and engaging

the wiper 148 in the vicinity of the stud 150. The block 224 is detachably mounted on an arm 226 which is pivotally mounted on a stud 228 on the arm 154 to swing in directions lengthwise of the shoe. A spring-pressed pin 230 in the arm 154 engages the outer end of the arm 226 and tends to swing the wiper 220 in a rearward direction toward the toe end of the shoe, the normal position of this wiper relatively to the wiper 148 being determined by engagement of the arm 226 with a shoulder 232 on the arm 154. The wiper 220, as shown in Fig. 1, further includes under the plate 222 a thin plate 234 which is curved to present a concave face toward the portion of the margin of the shoe bottom on which it acts and is resiliently flexible to permit it to adjust itself to the contour of the shoe bottom. It will be understood that the action of the auxiliary wiper on the shoe results from the swinging movement of the arm 154, this wiper being wedged inwardly between the front end portion of the wiper 148 and the downwardly inclined margin of the shoe bottom. The movement of the wiper 220 lengthwise of the shoe may be stopped by the resistance of the shoe before the arm 154 completes its movement, whereupon the spring-pressed pin 230 yields to permit continued movement of the arm 154.

The levers 158 by which the wipers are operated as above described have formed thereon gear sectors 236 in engagement with each other to equalize the swinging movements of the levers. For operating the levers there are provided two pistons 238 mounted in a cylinder 240 formed in the casting 40, the pistons having at their inner ends bosses 242 of reduced diameter to provide an annular space to receive operating fluid when the pistons are in engagement with each other at the limits of their inward movements. At its outer end each piston engages a pair of rolls 244 mounted on the rear end of the corresponding lever 158. A spring 246 connected to the levers 158 serves to retract the wipers and to return the pistons to their innermost positions. Operating fluid is admitted to the cylinder 240 from a pipe line 248 (Fig. 1) leading from the source of supply. The outward movements of the pistons in operating the wipers are limited by their engagement with stop blocks 250, one of which is shown in Fig. 2, these blocks being adjustable toward and from each other by means not herein shown in detail.

When the wipers have substantially completed their operative movements the toggle 32 (Fig. 1) is broken by means hereinafter described to release the lever 2 and thereby to permit the shoe to be forced more firmly up against the wipers by the toe rest 134 which is subject to the force of the operating fluid. Such release of the lever 2 permits upward movement of the shoe rest member 10 which is mounted on this lever and engages the ball portion of the shoe. Since the other shoe-rest member 50 engaging the toe end of the shoe is controlled by the lever 2 through the links 80, the lever 84 and the screw 96, as hereinbefore explained, the release of the lever 2 by the toggle also permits upward movement of the member 50. To insure, however, that adequate pressure will be applied by the wipers to the portions of the margin of the upper located near the beginning of the shank portion of the shoe, the construction is such as to prevent the member 50 from being moved as far upwardly by the pressure of the shoe thereon as the member 10. For this purpose there is threaded in the

frame a vertical rod 252, the lower end of the rod being located over the front arm of the lever 84 to limit adjustably as desired the upward movement of the shoe-rest member 50.

For breaking the toggle 32 to cause the shoe to be forced more firmly up against the wipers as above described, there is provided an arm 254 (Figs. 1 and 2) arranged to engage the front end of the screw 44 mounted in the toggle link 36. This arm is fast on a short shaft 256 mounted to turn in an extension of the left-hand stop block 250 and having fast on its lower end another arm 258 arranged to be engaged by one of the rolls 244 on the rear end of the left-hand wiper-operating lever 158. The arm 258 is so positioned on the shaft relatively to the arm 254 as to prevent the breaking of the toggle until the wipers have nearly completed their operative movements. Since the shaft 256 is carried by the adjustable stop block 250, the proper time relation between the termination of the movements of the wipers and the breaking of the toggle is maintained whatever may be the adjustment of the stop block.

While the operation of the machine as a whole is fully described in application Serial No. 189,407 of which the present application is a division, the manner in which the wipers are operated and controlled will be herein summarized. In presenting the shoe to the machine the operator engages its toe-end face with the leather facing 72 on the shoe-rest member 50 and by such engagement moves this member in a rearward direction until the margin of the upper at the sides of the ball portion of the shoe is in proper relation to the grippers 146 as determined by sight. By the movement thus imparted to the shoe-rest member 50 the studs 210 (Fig. 2) are adjusted to positions for properly determining thereafter the limits of movement lengthwise of the shoe of the supplemental wipers 202.

The shoe having thus been presented, the side clamps 98 are moved inwardly to clamp and position the shoe between them, the toe rest 134 is moved upwardly to clamp it against the shoe rest members 10 and 50, and the grippers are operated to pull the upper, all as disclosed in the last-mentioned application. After the pulling of the upper by the grippers the fluid is admitted to the cylinder 240 (Fig. 2) for operating the wipers. By the resulting inward swinging movements of the front arms of the levers 158 the wiper-carrying arms 154 are swung inwardly through the action of the links 174 and the plates 178 which connect the levers to these arms. The directions in which the arms 154 are thus moved is such that the main wipers 148 and the supplemental wipers 202 have substantial components of movement lengthwise of the shoe toward its toe end as they are moved bodily inward, the rolls 166 on the rear ends of the wipers 148 moving rearwardly along the slots 164 in the plates 162 carried by the levers 158 and the rear ends of these wipers, along with the supplemental wipers 202, being moved inwardly through these plates simultaneously with the swinging of the arms 154. The components of rearward movement imparted to the supplemental wipers 202 at this time cause the links 206 to move rearwardly until stopped by the studs 210 which thereby determine the limits of the rearward movements of the supplemental wipers. Substantially at the time when the wipers arrive in positions to act on the upper the grippers are opened to release the upper.

11

The first portion of the wiping operation of the wipers on the upper is effected by the above-described bodily movements thereof widthwise and lengthwise of the shoe, the auxiliary wipers 220 at this time being wedged yieldingly inward by the swinging of the arms 154 between the wipers 148 and the portions of the bottom of the shoe which are inclined downward heelwardly of the ball line. When the wipers have arrived substantially in the positions illustrated in Fig. 3, at which time the wiping operation has been substantially completed heelwardly of the ball line but only begun in locations nearer the toe end of the shoe, the swinging of the arms 154 ceases by reason of the relation of the plates 178 to the rolls 188 while the front arms of the levers 158 continue their inward swinging movements. In response to such further movements of these arms the wipers 148, together with the supplemental wipers 202, are swung inwardly about the studs 150, located at this time substantially at the heelward end of the ball portion of the shoe, through the action of the plates 162 on the rolls 166, thus completing the wiping operation as illustrated in Fig. 4. As hereinbefore fully explained, the arms 154 are, through the action of the plates 178, locked at this time against any retractive movements. As the wipers are thus swung inwardly the links 206 approach a parallel relation and thereby impart to the wipers 202 short heelward movements relatively to the wipers 148. Substantially at the end of the wiping operation the toggle 32 (Fig. 1) is broken by the arm 254 to release the lever 2 and thereby also to release the lever 84. This permits the shoe to be forced more firmly up against the wipers by the toe rest 134 to increase the pressure of the wipers on the margin of the upper. Since the rod 252 permits at this time only a very short upward movement of the shoe-rest member 50 which engages the bottom of the toe end of the shoe, while the shoe rest member 10 engaging the ball portion of the shoe can move farther upwardly, the tendency of the toe rest is to rock the shoe in the direction to raise its heel end and thus to insure that adequate pressure will be applied by the wipers to the portions of the margin of the upper near the beginning of the shank portion of the shoe.

Having thus described the invention, what I claim as new and desire to secure by Letters Patent of the United States is:

1. In a lasting machine, means for wiping the marginal portion of the upper of a shoe on a last inwardly over the bottom of the last at the opposite sides of the ball portion of the shoe, said wiping means comprising at each side of the shoe beyond its toe portion a pair of wipers arranged to extend continuously one beyond the other along the side of the shoe and relatively movable lengthwise of the shoe while maintaining such continuity, a member arranged to engage the toe end face of the shoe, and means for effecting variably as determined by said member such relative movement of the wipers in the operation of the machine on shoes of different sizes to vary the distance lengthwise of the shoes of their engagement with the uppers.

2. In a lasting machine, means for wiping the marginal portion of the upper of a shoe on a last inwardly over the bottom of the last at the opposite sides of the ball portion of the shoe, said wiping means comprising at each side of the shoe beyond its toe portion a pair of wipers arranged to extend continuously one beyond the other

12

along the side of the shoe and relatively movable lengthwise of the shoe while maintaining such continuity, a member arranged to engage the toe-end face of the shoe and mounted for movement by the shoe as the shoe is presented to the machine, and means for effecting variably as determined by the position of said member such relative movement of the wipers in the operation of the machine on shoes of different sizes to vary the distance lengthwise of the shoes of their engagement with the uppers.

3. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and connected together for relative swinging movement lengthwise of the shoe about an axis extending heightwise of the shoe while maintaining such continuity, and means for effecting variably such relative swinging movement of the wipers in the operation of the machine on shoes of different sizes to vary the distance lengthwise of the shoes of their engagement with the uppers.

4. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe, that wiper of each pair which is nearest to the toe end of the shoe being mounted to swing relatively to the other wiper about an axis extending heightwise of the shoe to vary its extent beyond the other wiper while maintaining such continuity with the other wiper, and means for variably swinging the wiper thus mounted in the operation of the machine on shoes of different sizes to vary the distance lengthwise of the shoes of the engagement of the pair of wipers with the uppers.

5. In a lasting machine, means for wiping the marginal portion of the upper of a shoe on a last inwardly over the bottom of the last at the opposite sides of the ball portion of the shoe, said wiping means comprising at each side of the shoe beyond its toe portion a pair of wipers arranged to extend continuously one beyond the other along the side of the shoe and relatively movable lengthwise of the shoe while maintaining such continuity, and means for effecting variably such relative movement of the wipers as determined by the position of each shoe lengthwise in the machine to terminate the engagement of the wipers with the upper at the same distance from the end of the toe of each shoe regardless of variations in the positions of the different shoes.

6. In a lasting machine, means for wiping the marginal portion of the upper of a shoe on a last inwardly over the bottom of the last at the opposite sides of the ball portion of the shoe, said wiping means comprising at each side of the shoe beyond its toe portion a pair of wipers arranged to extend continuously one beyond the other along the side of the shoe and relatively movable lengthwise of the shoe while maintaining such continuity, a member arranged to engage the toe-end face of each shoe and thus to assume a position determined by the position of the shoe lengthwise in the machine, and means for effecting variably as determined by said member such relative movement of the wipers lengthwise of the shoe to terminate the engagement of the

wipers with the upper at the same distance from the end of the toe of each shoe regardless of variations in the positions of the different shoes.

7. In a lasting machine, means for wiping the marginal portion of the upper of a shoe on a last inwardly over the bottom of the last at the opposite sides of the ball portion of the shoe, said wiping means comprising at each side of the shoe beyond its toe portion a pair of wipers arranged to extend continuously one beyond the other along the side of the shoe and relatively movable lengthwise of the shoe while maintaining such continuity, a member arranged to engage the toe-end face of each shoe and mounted for movement by the shoe as the shoe is presented to the machine, and means for effecting variably as determined by the position of said member such relative movement of the wipers lengthwise of the shoe to terminate the engagement of the wipers with the upper at the same distance from the end of the toe of each shoe regardless of variations in the positions of the different shoes.

8. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe, that wiper of each pair which is nearest to the toe end of the shoe being mounted to swing relatively to the other wiper about an axis extending heightwise of the shoe to vary the distance lengthwise of the shoe of its engagement with the upper while maintaining such continuity with the other wiper, and means for variably swinging the wiper thus mounted as determined by the position of each shoe lengthwise in the machine to terminate the engagement of the wipers with the upper at the same distance from the end of the toe of each shoe regardless of variations in the positions of different shoes.

9. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two pairs of wipers inwardly widthwise of the shoe with components of movement lengthwise of the shoe toward its toe end, and means for variably limiting in the operation of the machine on different shoes that component of movement of the wiper of each pair which is nearest to the toe end of the shoe independently of the movement of the other wiper of the pair.

10. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two pairs of wipers inwardly widthwise of the shoe with components of movement lengthwise of the shoe toward its toe end, a member arranged to engage the toe end face of each shoe, and means for variably limiting as determined by said member the component of movement lengthwise of the shoe of the wiper of each

pair which is nearest to the toe end of the shoe independently of the movement of the other wiper of the pair.

11. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two pairs of wipers inwardly widthwise of the shoe with components of movement lengthwise of the shoe toward its toe end, a member arranged to engage the toe-end face of each shoe and mounted for movement by the shoe as the shoe is presented to the machine, and means adjustable by the movement of said member for limiting the component of movement lengthwise of the shoe of the wiper of each pair which is nearest to the toe end of the shoe independently of the movement of the other wiper of the pair.

12. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two pairs of wipers inwardly widthwise of the shoe with components of movement lengthwise of the shoe toward its toe end, a member arranged to engage the toe-end face of each shoe and mounted for movement by the shoe as the shoe is presented to the machine, stop means arranged to be variably positioned by the movement of said member, and members connected to those wipers which are nearest to the toe end of the shoe and arranged to engage said stop means to limit the components of movement of those wipers lengthwise of the shoe independently of the movements of the other wipers.

13. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two pairs of wipers inwardly widthwise of the shoe with components of movement lengthwise of the shoe toward its toe end, members connected to those wipers which are nearest to the toe end of the shoe and movable thereby lengthwise of the shoe, and stop means arranged to engage said members to limit variably in the operation of the machine on different shoes the components of movement lengthwise of the shoe of those wipers independently of the movements of the other wipers.

14. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two pairs of wipers inwardly

widthwise of the shoe with components of movement lengthwise of the shoe toward its toe end, links pivotally connected to those wipers which are nearest to the toe end of the shoe and movable thereby lengthwise of the shoe, and stops arranged to engage said links to limit variably in the operation of the machine on different shoes the components of movement lengthwise of the shoe of those wipers independently of the movements of the other wipers.

15. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two wipers of each pair bodily inward widthwise of the shoe with components of movement lengthwise of the shoe toward its toe end and for thereafter swinging them as a unit farther inward about an axis located substantially at the heelward end of the ball portion of the shoe, and means for moving that wiper of each pair which is nearest to the toe end of the shoe relatively to the other wiper in a direction toward the heel end of the shoe in the course of such inward swinging movements of the wipers.

16. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two wipers of each pair bodily inward widthwise of the shoe with components of movement lengthwise of the shoe toward its toe end and for thereafter swinging them as a unit farther inward about an axis located substantially at the heelward end of the ball portion of the shoe, and means responsive to such swinging movements of the wipers to move that wiper of each pair which is nearest to the toe end of the shoe relatively to the other wiper in a direction toward the heel end of the shoe.

17. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two wipers of each pair bodily inward widthwise of the shoe with components of movement lengthwise of the shoe toward its toe end and for thereafter swinging them as a unit farther inward about an axis located substantially at the heelward end of the ball portion of the shoe, and links pivotally connected respectively to those wipers which are nearest to the toe end of the shoe and mounted for swinging movements to move those wipers relatively to the other wipers in directions toward the heel end of the shoe in the course of such inward swinging movements of the wipers.

18. In a lasting machine, means for wiping the marginal portion of the upper of a shoe on a

75

last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two wipers of each pair bodily inward widthwise of the shoe with components of movement lengthwise of the shoe toward its toe end and for thereafter swinging them as a unit farther inward about an axis located substantially at the heelward end of the ball portion of the shoe, and means for variably limiting in the operation of the machine on different shoes the component of movement lengthwise of the shoe of that wiper of each pair which is nearest to the toe end of the shoe independently of the movement of the other wiper of the pair, said limiting means being arranged to move the wipers located nearest to the toe end of the shoe in a heelward direction relatively to the other wipers in the course of the inward swinging movements of the wipers.

25 19. In a lasting machine, means for wiping the marginal portion of the upper of a shoe on a last inwardly over the bottom of the last at the opposite sides of the ball portion of the shoe, said wiping means comprising at each side of the shoe a pair of wipers arranged to extend continuously one beyond the other along the side of the shoe and relatively movable lengthwise of the shoe while maintaining such continuity, means for moving the two wipers of each pair bodily inward widthwise of the shoe with components of movement lengthwise of the shoe toward its toe end and for thereafter swinging them as a unit farther inward about an axis located substantially at the heelward end of the ball portion of the shoe, and means for variably limiting in the operation of the machine on different shoes the component of movement lengthwise of the shoe of that wiper of each pair which is nearest to the toe end of the shoe independently of the movement of the other wiper of the pair, said limiting means including links pivotally connected to the wipers which are nearest to the toe end of the shoe and arranged to swing during the inward swinging movements of the wipers and thereby to move the wipers located nearest to the toe end of the shoe in heelward directions relatively to the other wipers.

20 20. In a lasting machine, wipers for wiping the marginal portion of the upper of a shoe on a last inwardly over the bottom of the last at the opposite sides of the ball portion of the shoe respectively, arms mounted for swinging movements widthwise of the shoe about axes extending heightwise of the shoe for moving inwardly portions of the wipers located farthest from the toe end of the shoe, other arms mounted for swinging movements about axes extending heightwise of the shoe for moving inwardly portions of the wipers located nearer the toe end of the shoe during the swinging of the first-named arms and for thereafter swinging the wipers farther inward relatively to the first-named arms, and connections between said first-named arms and said other arms for first swinging the first-named arms inwardly by the inward movements of said other arms and for thereafter holding the first-named arms positively against retractive movements during further inward movements of said other arms alone.

21. In a lasting machine, wipers for wiping

the marginal portion of the upper of a shoe on a last inwardly over the bottom of the last at the opposite sides of the ball portion of the shoe respectively, arms mounted for swinging movements widthwise of the shoe about axes extending heightwise of the shoe for moving inwardly portions of the wipers located farthest from the toe end of the shoe, other arms mounted for swinging movements about axes extending heightwise of the shoe for moving inwardly portions of the wipers located nearer the toe end of the shoe during the swinging of the first-named arms and for thereafter swinging the wipers farther inward relatively to the first-named arms, connections between said first-named arms and said other arms for swinging the first-named arms inwardly by the movements of said other arms, said connections comprising members movable relatively to the first-named arms into positions to terminate the movements of those arms prior to the completion of the movements of said other arms, and means for thus moving said members by the movements of said other arms.

22. In a lasting machine, wipers for wiping the marginal portion of the upper of a shoe on a last inwardly over the bottom of the last at the opposite sides of the ball portion of the shoe respectively, arms mounted for swinging movements widthwise of the shoe about axes extending heightwise of the shoe for moving inwardly portions of the wipers located farthest from the toe end of the shoe, other arms mounted for swinging movements about axes extending heightwise of the shoe for moving inwardly portions of the wipers located nearer the toe end of the shoe during the swinging of the first-named arms and for thereafter swinging the wipers farther inward relatively to the first-named arms, connections between said first-named arms and said other arms for swinging the first-named arms inwardly by the movements of said other arms, said connections including members having slots therein and other members lying in said slots, said first-named members being mounted for movements to position their slots in such relation to said other members as to terminate the movements of the first-named arms prior to the completion of the movements of said other arms, and means for thus moving said first-named members by the movements of said other arms.

23. In a lasting machine, wipers for wiping the marginal portion of the upper of a shoe on a last inwardly over the bottom of the last at the opposite sides of the ball portion of the shoe respectively, arms mounted for swinging movements widthwise of the shoe about axes extending heightwise of the shoe for moving inwardly portions of the wipers located farthest from the toe end of the shoe, other arms mounted for swinging movements about axes extending heightwise of the shoe for moving inwardly portions of the wipers located nearer the toe end of the shoe during the swinging of the first-named arms and for thereafter swinging the wipers farther inward relatively to the first-named arms, connections between said first-named arms and said other arms for swinging the first-named arms inwardly by the movements of said other arms, said connections including plates having slots therein and movable bodily by said other arms and also including members carried by said first-

named arms and lying in said slots, said plates being mounted for swinging movements to position their slots in such relation to said members as to terminate the movements of the first-named arms prior to the completion of the movements of said other arms, and means for thus swinging said plates by the movements of said other arms.

24. In a lasting machine, wipers for wiping the marginal portion of the upper of a shoe on a last inwardly over the bottom of the last at the opposite sides of the ball portion of the shoe respectively, arms mounted for swinging movements widthwise of the shoe about axes extending heightwise of the shoe for moving inwardly portions of the wipers located farthest from the toe end of the shoe, other arms mounted for swinging movements about axes extending heightwise of the shoe for moving inwardly portions of the wipers located nearer the toe end of the shoe during the swinging of the first-named arms and for thereafter swinging the wipers farther inward relatively to the first-named arms, and connections between said first-named arms and said other arms for swinging the first-named arms inwardly by the movements of said other arms, said connections including members movable by said other arms relatively to the first-named arms into positions to terminate the movements of the first-named arms prior to the completion of the movements of said other arms and also including members arranged to cooperate with said first-named members to hold the first-named arms positively against retractive movements during the further movements of said other arms.

25. In a lasting machine, wipers for wiping the marginal portion of the upper of a shoe on a last inwardly over the bottom of the last at the opposite sides of the ball portion of the shoe respectively, arms mounted for swinging movements widthwise of the shoe about axes extending heightwise of the shoe for moving inwardly portions of the wipers located farthest from the toe end of the shoe, other arms mounted for swinging movements about axes extending heightwise of the shoe for moving inwardly portions of the wipers located nearer the toe end of the shoe during the swinging of the first-named arms and for thereafter swinging the wipers farther inward relatively to the first-named arms, connections between said first-named arms and said other arms for swinging the first-named arms inwardly by the movements of said other arms, said connections including members having slots therein and other members lying in said slots, said first-named members being mounted for movements to position their slots in such relation to said other members as to prevent any further movements of the first-named arms by continued movements of said other arms while preventing positively any retractive movements of the first-named arms, and means for thus moving said first-named members by the movements of said other arms.
